UNITED STATES PATENT OFFICE.

NATHAN ROSENBERG, OF NORTH TARRYTOWN, NEW YORK.

LIQUID-FUEL BURNER.

1,098,642.

Specification of Letters Patent.

Patented June 2, 1914.

Application filed March 12, 1914. Serial No. 824,104.

To all whom it may concern:

Be it known that I, NATHAN ROSENBERG, a citizen of the United States, and resident of North Tarrytown, county of Westchester, State of New York, have invented certain new and useful Improvements in Liquid-Fuel Burners, of which the following is a specification.

This invention relates to burners for oil and other liquid fuel.

More particularly the invention comprises an inflow element connected to the source of liquid fuel supply, ports for the admission of air to the burning fuel, and means for controlling the resulting flame fed by the fuel. Preferably, the inflow element comprises a dish-shaped receptacle into which the liquid fuel flows from an inlet opening disposed above the bottom of such receptacle, and the air is supplied through one or more openings in a hood-like inclosure disposed above such receptacle. The means for controlling the resulting flame or flames may comprise one or more deflectors disposed in a determined position relative to the fuel inlet element. The character of the flame is determined by the structure of the deflector, the relation of the deflector to the fuel inlet element and such other variable relationship as will appear more fully hereinafter.

Other features and objects of my invention will be more fully understood from the following description and the accompanying drawings, in which—

Figure 1 shows one form of my invention, the portion to the left being a side elevation and that to the right being a central sectional elevation on the line 1—1 of Fig. 2, looking in the direction of the arrow; Fig. 2 is a top plan view of the same, omitting the top deflector; Fig. 3 is an end elevation; and Fig. 4 is a central sectional elevation on the line 4—4 of Fig. 2.

Referring to the drawings, the burner comprises the inlet 1 connected to the source of liquid fuel supply by the piping 2. Preferably, the inlet 1 is a pipe 3 having its lower end 4 screw threaded to the piping 2, the upper flattened end 5 of pipe 3 being disposed at the apex of the curved cone-like element 6, positioned at or toward the center of the dish-shaped receptacle 7 having a curved bottom. It is preferred to flatten the end 5 to form a substantially rectangular opening, the sides of which are disposed

substantially parallel to the contour of the substantially rectangular receptacle 7, as shown, whereby to secure uniform flow of the fluid from the outlet 5 into the receptacle 7. The flow of the liquid fuel from the source of supply, say a tank, is controlled by a suitable cock or valve, and the fuel thus controlled flows over and down the sides of curved cone-like element 6 into the curved bottom of the receptacle 7. When the burner is ignited, the fuel flowing out of the outlet 5 is heated and will burn the area of burning fuel extending over the fuel contained in the receptacle 7.

Air for effecting and completing the combustion of the fluid fuel enters the openings 8, 9, communicating with the interior of the hood 10. The hood 10 is preferably supported by the extension 11 projecting from the upper edge of the receptacle 7. I have shown the extension to be substantially rectangular in shape extending laterally on all four sides of the receptacle 7, and having strips 12 for retaining the hood 10 in position thereon. The hood 10 may be made of corresponding halves 13, 14, with overlapping flanges 15, along the meeting edges. The hood halves are shown to be held together by bolts 17. The hood may be made of cast iron, or steel or the like, and by the use of the overlapping flanges and the bolts or the like the hood parts will be prevented from spreading due to high temperature. I have shown the hood 10 to be formed of a central dome 18 and bulged side chambers 19, 19, although such arrangement may be varied as will be understood by those skilled in the art.

In the specific arrangement thus described, the air entering the openings 8, 9, flows through the respective bulged chambers 19, 19, into the respective connecting passages 20, 20, and thence into the dome chamber 18 of relatively large volume, thence downwardly through the large opening 21 formed by the depending ring or lip 22, and finally into intimate mixture with the hot vapor of the heated fuel. As one form of means for controlling the resulting flame, I have indicated the deflector 23 supported by or extending from one side of the hood 10. Such deflector 23 is suitable when it is desired to heat a baking oven suitably positioned on the same side of the hood 10 as the deflector 23. The relation of the deflector 23 to the fuel supporting

means as approximately indicated in the drawings results in a flame which has a relatively wide combustion area, such as would be required for baking purposes. I have indicated the deflector 24 on the opposite side of the hood 10; and similarly supported by or extending from the hood 10. Such relation of the deflector 24 to the means supporting the burning fuel result in a flame suitable for heating a water back or like device by means of a relatively localized flame.

It will be noted that the deflector 23 for securing a relatively wide combustion area is disposed at a greater distance from the receptacle 7 than the deflector 24, the latter effecting a flame of relatively narrow combustion area.

When it is desired to employ my burner to heat a furnace or like device utilizing a very large or extended flame such flame will be secured by omitting the deflectors 23 and 24, and using the deflector 25 shown in the form of an inverted cone supported above the hood 10, as by the circular flange 27 engaging the upwardly extending boss 28 on the top of hood 10. Of course, other supporting means for the deflector 25 may be employed.

The deflectors 23, 24, may be removably supported at the sides of hood 10, or may be cast integrally with the respective hood halves 13, 14. If desired, the flow of the air into the openings of the hood may be regulated by a suitable regulator. Ordinarily, the proper flow of air will be controlled automatically by the hood comprising the central dome chamber 18 of relatively large volume and subjected to high heat into which the air flows from one or more sides from the bulged chambers 19, 19, through the somewhat restricted connecting passages 20, 20. I have indicated the burner as of a general rectangular shape, but such shape may be varied to attain the objects desired. It is desirable to make all portions of the air inflow and outflow openings with flaring edges and the air chambers with rounded surfaces without corners, whereby no retarding surfaces are presented to the air flow. It is also advantageous to give the cone-like element a curved surface, and to form the bottom and sides of the fuel receptacle of curved surfaces, whereby the vapors of the fuel fanned by the air supplied through the hood are thoroughly intermixed and result in a flame of complete combustion and high heat.

It will be clear that my burner is suitable for the use of any liquid or other fluid fuel, including crude oil and other carbonaceous fuel of high viscosity, suitable changes or modifications if necessary being made to secure the above described objects of my invention.

What I claim and desire to secure by Letters Patent is:—

1. In a burner or the like, the combination of an inlet, a receptacle for supporting the fuel disposed below the opening of said inlet, an air hood comprising a dome portion of relatively large volume and an air inlet portion, said dome portion being disposed above said receptacle and having an air outlet adjacent said receptacle, said dome including its air outlet being free from obstructing parts, and a deflector disposed above and spaced from the sides of said receptacle. 70

2. In a burner or the like, the combination of a fuel inlet, a receptacle for supporting the fuel disposed about said inlet, an air hood for admitting air to the vapors produced upon heating said fuel, said air hood comprising a dome portion disposed above 85 said receptacle, said dome portion comprising an air outlet disposed above the bottom of said receptacle but below said inlet, and a deflector positioned above and spaced at a distance from the sides of said receptacle. 90

3. In a burner or the like, the combination of a substantially rectangular receptacle, a fuel supply inlet having an opening disposed substantially centrally of the sides of said receptacle, an air hood having a length 95 greater than its width disposed with its length substantially parallel to the length of said receptacle, said air hood comprising a central dome portion of relatively large volume and oppositely disposed chambers communicating with said dome portion, said dome portion having an air outlet disposed above and adjacent said receptacle, and a deflector positioned to be spaced above and from said receptacle and extending 100 lengthwise of said hood. 105

4. In a burner or the like, the combination of a support having oppositely disposed air openings, an air hood carried by said support, said air hood comprising oppositely 110 disposed chambers having openings respectively registering with said oppositely disposed air openings, said air hood further comprising a central dome portion of relatively large volume communicating with 115 said oppositely disposed chambers, and a receptacle for the fuel carried by said support, said dome portion having an air outlet disposed above and adjacent to said receptacle. 120

5. In a burner or the like, the combination of a receptacle for the burning fuel, an air hood disposed above and vertically within the outer boundary of said receptacle, and a plurality of vanes in determined relation to said receptacle and said hood for regulating the area of the produced flame, one of said vanes being on one side of said hood, another of said vanes being on another side of said hood and disposed at a less distance 125 130

from said receptacle than said vane on the other side.

6. In a burner or the like, the combination of a substantially rectangular receptacle for the burning fuel, a substantially rectangular air hood disposed above and vertically within the two longer sides of said receptacle, a vane on one side of said hood, and a second vane on the opposite side of said hood, said second vane being at a greater distance from 10 said receptacle than said first-named vane.

In testimony whereof I have signed this specification in the presence of two subscribing witnesses.

NATHAN ROSENBERG.
